UNITED STATES PATENT OFFICE.

HARRY RANDOLPH VAN DEVENTER, OF SUMTER, SOUTH CAROLINA, ASSIGNOR TO
SPLITDORF ELECTRICAL COMPANY, OF NEWARK, NEW JERSEY, A CORPORATION
OF NEW JERSEY.

TERMINAL FOR DYNAMOS.

1,261,193.

Specification of Letters Patent.

Patented Apr. 2, 1918.

Application filed June 10, 1916. Serial No. 102,949.

To all whom it may concern:

Be it known that I, HARRY RANDOLPH VAN DEVENTER, a citizen of the United States, residing at Sumter, in the county of 5 Sumter and State of South Carolina, have invented certain new and useful Improvements in Terminals for Dynamos, of which the following is a specification, reference being had to the accompanying drawing.

10 My invention relates to ignition dynamos commonly called magnetos and has for its object the provision of a magneto in which the coil terminal is mounted upon the coil, so the conducting cable may be easily and 15 quickly attached and detached thereto.

Another object is to eliminate all brushes in the connection between the winding and the cable leading from the magneto to the spark plug or other device.

20 A further object is to provide a compact arrangement in which the winding and the terminal therefor may be removed from the magneto as a unit.

For the sake of illustration, I describe 25 my invention as applied to a magneto of the well known "Dixie" type. As the construction and operation of such magnetos are well known, I will only describe same sufficiently to enable my invention to be understood.

30 Reference being had to the accompanying drawing, 1 denotes the winding or windings of the magneto. These are wound about a core 2, which is removably supported in the 35 pole pieces 3 and 4. The winding has insulating heads 5 and 6 of any suitable material, and 6 is formed with the projecting portion 7, in which is embedded a suitable terminal 8, to which is connected one end of 40 the winding. The head 6 may be of any suitable form, arranged so that the projecting part 7 may pass through the apertured side plate 9 of the magneto. This plate has an annular extended portion 10, adapted to 45 be embraced by the soft rubber cap 11, surrounding the cable 12, which has secured to its end the terminal pin 13 adapted to make contact with the socket terminal 8 or to connect to any suitable arrangement in any 50 suitable manner.

By removing the side cover plates 9 and 14, the coil structure may be removed from the magneto as a unit, by merely pulling the

cable 12 out of the socket; and there are no brushes or contacts any where in the circuit 55 between the cable 12 and the winding on the coil except the contact between 13 and 8. It will also be noted that I eliminate entirely the expense and complication incident to mounting a terminal for the cable 12 60 upon the side cover plate 9 as has heretofore been done, which necessitates a brush or other contact connection between the said terminal and the terminal for the winding carried on the head of the coil. 65

I further eliminate the disadvantages existing in arrangements wherein the cable 12 is permanently lashed to or otherwise attached to the unit, for when it is necessary to take the coil out of the magneto, and the 70 cable is attached, difficulty is experienced unless the cable is disconnected from the coil.

While I have described one embodiment 75 of my invention, it is obvious that modifications can be made in the mounting and shape of the coil head carrying the terminal 8 without however departing from the invention as herein claimed:

1. In an ignition dynamo, a generating 80 winding having heads, a circuit terminal embedded in one of said heads and having an outwardly projecting portion, a cover plate adjacent said outwardly projecting portion of said terminal and apertured to 85 receive the latter, and a conductor having a terminal adapted to connect with said first mentioned terminal, substantially as described.

2. In an ignition dynamo, a generating 90 winding, an insulating head therefor, a terminal embedded in said head the latter having a projecting portion, a cover for said dynamo having an aperture through which the projecting portion of said head may be 95 reached, and a conductor passing through said apertured cover and connected to said terminal, substantially as described.

3. In an ignition dynamo having fixed pole pieces, a unit structure comprising a 100 core bridging said pole pieces and carrying a stationary generating winding, heads for the winding, said core heads and winding comprising a removable unitary structure, a spark plug cable leading into said dynamo 105 and a socket terminal on said unitary struc-

ture to which said cable may be joined, substantially as described.

4. In an ignition dynamo having stationary pole pieces, a core connecting said pole pieces, heads on said core and a winding between the heads, said core heads and winding forming a unit structure removable from said dynamo and normally stationary

therein, a socket terminal carried upon said unit structure and connected to said winding and a spark plug cable leading into said dynamo and joined to said terminal. 10

In testimony whereof I hereunto affix my signature.

HARRY RANDOLPH VAN DEVENTER.
